COMBINED TABLE AND IRONING BOARD

Alonza Sealy, New York, N. Y.

Application June 1, 1948, Serial No. 30,355

4 Claims. (Cl. 38—115)

1

My invention relates to ironing boards, and more particularly to such boards as are adapted to be combined with a table or like supporting means, whereby the ironing board is movable to and from a concealed and inoperative position and an operative position.

With the foregoing in view, an object of my invention is to provide an improved ironing board and support for the same.

A further object is to provide an improved means for mounting an ironing board on a support for the same, together with improved means for moving the ironing board to and from the retracted and concealed position and an advanced and operative position.

A further object is to provide a support including a service top, laterally-movable means carried by the support and including a forward end movable to and from a concealed position below the top and an advanced position laterally outwardly of the top, said movable means including means mounting an ironing board for upward movement to and from a lowered position below said top and a raised position above said top.

Other objects and advantages reside in the particular structure of the invention, the structure of the elements thereof, combination and arrangement of such elements, and will be readily understood by those skilled in the art upon reference to the attached drawing in connection with the following specification, wherein the invention is shown, described and claimed.

In the drawings:

Figure 1 is a perspective view showing the ironing board according to the invention in an operative position relative to its support;

Figure 2 is a plan view of the ironing board showing the same in the retracted position relative to the support, parts of the support being broken away and shown in horizontal section;

Figure 3 is a transverse vertical sectional view taken substantially on the plane of the line 3—3 of Figure 2, but showing the parts in the operative position;

Figure 4 is a transverse vertical sectional view taken substantially on the plane of the line 4—4 of Figure 3;

Figure 5 is an enlarged fragmentary vertical sectional view taken substantially on the plane of the line 5—5 of Figure 4;

Figure 6 is a fragmentary perspective view on an enlarged scale showing an element of the invention apart from the rest of the structure.

Referring specifically to the drawings, wherein like reference characters have been used through-

2

out the several views to designate like parts, 10 designates generally a suitable support for the ironing board according to the invention. As shown, the support 10 may comprise a table supported by one or more vertical legs 11, and which includes a service top 12 fixed to the upper ends of the legs. The table 10 may include side frame members or rails 13, a rear frame member or rail 14 and a front frame member or rail 15 connecting said legs together. The front frame member 15 is formed with an opening therein. The frame members 13, 14 and 15 may be spanned by a floor 16 in downwardly-spaced relation to the top 12, whereby to provide a closed space 15 below the top. As so far described, the structure of the support 10 is conventional and forms no part of the invention.

The opening in the front frame member 15 is closed by a suitable closure 17 hinged to the support 10 by any suitable hinges 18. The closure 17 may have the conventional handle or pull 19 fixed to the outer surface thereof, and the upper edge may be formed with a latch detent 20 adapted to cooperate with any suitable latch, not shown, carried by the under surface of the top 12 to retain the closure 17 in closed position. As is readily apparent from Figures 1 and 3, the closure 17 is swingable from a closed position downwardly to an open position substantially below the plane of the lower edge of the opening formed in the frame member 15. The upper surface of the floor 16 is provided with a pair of laterally-spaced forwardly-extending rails or guide bars 21 providing a slideway for a runner 23 formed on the bottom of a utility drawer 22. The drawer 22 may be provided with a conventional pull 24 on the forward wall thereof. As is readily apparent from Figure 4, the drawer 22 is substantially narrower than the opening in the front frame member 15, whereby to provide spaces laterally outwardly of each side of the drawer.

A base member or carriage for the ironing board is carried by the support 10 below the top 12 and is movable substantially horizontally of the support to and from an advanced position outwardly of the top and a retracted position below the top. Such base member or carriage may comprise a transverse slide or plate 25 having its ends slidable in slideway-providing grooves 26 formed in the inner surfaces of the side frame members 13. The base member may also include a pair of laterally-spaced runners 27 which are slidable on rail-providing portions of the opening 15 in the front frame member 15 on either

side of the drawer 22. Such runners 27 are preferably provided with suitable pulls 28 on the fixed forward ends 27' thereof to facilitate their withdrawal to the operative or advanced position. As is readily apparent from a comparison of Figures 2 and 3, the runners 27 include front ends which are advanced outwardly of the top 12 to an operative position and which are retracted below the top 12 to an inoperative position. The forward end of the base member is formed with at least one vertically or upwardly-directed slideway or slot now to be described. In the embodiment shown, there is a vertically or upwardly-directed slideway or slot 30 formed in the forward end of each runner 27. Such slideways or slots 30 are elongated and extend longitudinally of the runners 27 in the forward ends thereof. A pair of upwardly-directed legs 31, which are preferably shaped to be complementary to the slots 30, are upwardly-slidable in the slots from a lowered position with the upper ends of the legs below the top 12 of the support 10 and an elevated position with the upper ends of the legs positioned above the top 12. A suitable ironing board 32 is fixed to the upper ends of the legs 31 and spans the runners 27. Guide members 33 depend from the ironing board 32 in laterally inwardly-spaced relation to the legs 31 and slidably engage the inner surfaces of the runners 27. Such guide members 33 may be provided with parallel vertical slots 34 which engage headed stop members 35 to provide limit stops for upward movement of the ironing board 32 and legs 31. Likewise, the guide members 33 cooperate with the legs 31 and the vertical guideways 30 to provide a firm support for the ironing board 32 when the same is in the elevated position.

Latch means are provided to lock the legs 31 and ironing board 32 in the elevated position. Such latch means is best illustrated in Figure 6, and comprises an elongated block 40 which is slidable in a forwardly-directed slideway 41 formed in each of the runners 27. The block 40 is formed with an upwardly-directed surface 42 which is complementary to the lower end edge of the leg 31, whereby to provide a firm seat for such lower end edge of the leg, as will appear presently. Each block 40 is longitudinally bored, as at 44, for the sliding reception of a stem or pin 43 which extends longitudinally of each runner 27. Thus, each stem 43 provides a runner for each block 40. The rear ends of the stems 43 extend through suitable bosses 45 carried by the runners 27 and may be detachably secured to such bosses in any suitable manner, as by the nuts 46. A coil spring 47 surrounds each stem 43 between each boss 45 and the inner end of each block 40. If necessary, a washer 48 may be interposed between the forward end of the spring 47 and the inner end of each block 40. Each runner 27 is provided with upwardly-directed rail-providing surfaces 49 and 50 that slidably engage corresponding and complementary under surfaces of each block 40 to support the same during sliding movement, each block 40 being generally Z-shaped in transverse cross-section, Figure 4.

To operate the device, the closure 17 is first opened and the base member for the ironing board is pulled to the forwardly-extended position by means of the pulls 28. In this connection, it should be noted that the slide 25 includes opposite end portions which extend laterally behind the forward legs 11, whereby to engage

the rear surfaces thereof and provide limit stops limiting forward movement of the base member. This structure is readily seen in Figures 3 and 4, as well as Figure 2. The ironing board 32 is now 5 clear of the top 12 and may be raised from the broken line position, Figure 3, to the full line position of Figure 3, the springs 47 project the 10 latches 40 forwardly below the bottom edges of such legs. The complementary surfaces 42 and 15 bottom end edges of the legs 31 provide a firm base for the ironing board to prevent wobbling of the same in cooperation with the vertical guideway and depending guide member 33 aforesaid. As best seen in Figures 1 and 6, each latch 20 40 includes a portion extending laterally outwardly of the runners 27 and designated by the reference character 51. Such portions 51 provide finger grips when it is desired to move the ironing board to the lowered position. Thus, it 25 is only necessary to grasp the portions 51 by the hands and move the same and said latches rearwardly until the supporting surfaces 42 thereof clear the bottom end edges of the legs 31. Thereafter, the ironing board 32 and the legs 31 will drop by gravity to the lowered position and the base member may then be slid inwardly to the retracted position and the closure 17 closed. 30 The drawer 22 previously described comprises a convenient storage place for ironing accessories, such as the iron, its stand and other appurtenances thereto.

While I have shown and described what is now thought to be a preferred embodiment of the invention, it is to be understood that the same is susceptible of other forms and expressions. Consequently, I do not limit myself to the precise structure shown and described hereinabove except as hereinafter claimed.

I claim:

1. An ironing board attachment for a table having a top and a pair of laterally spaced substantially parallel rails disposed below the top and provided in their inner faces with opposed grooves, the attachment comprising a pair of longitudinally shiftable connected runners disposed beneath the top of the table and between the rails thereof and including parts slidably engaging within the grooves of the rails, the runners being provided near their forward ends with substantially vertical transverse openings, the tops of the runners having longitudinal recesses forming slideways which lead into the substantially vertical openings of the runners, an ironing board arranged adjacent to the forward ends of the runners and above the runners and including spaced depending legs slidably engaging in the substantially vertical openings of the runners, and spring pressed latch blocks slidably mounted within the slideways of the runners and biased longitudinally forwardly so that they project into the substantially vertical openings of the runners and beneath the depending legs of the ironing board to releasably hold the ironing board in a raised position.

2. In an ironing board attachment, a support including laterally spaced substantially horizontal rails, a longitudinally shiftable carriage 70 slidably mounted upon the rails and provided near its forward end with a substantially vertical opening, the carriage being provided in its top with a substantially horizontal longitudinal recess forming a slideway leading into the substantially vertical opening, an ironing board dis-

posed above the carriage and including a depending leg slidably engaging within the substantially vertical opening of the carriage, a longitudinally shiftable latch block slidably mounted within the slideway of the carriage, and resilient means connected with the latch block for urging it longitudinally forwardly and into the substantially vertical opening below the depending leg for releasably holding the ironing board in an elevated position.

3. In an ironing board attachment, a support including a pair of laterally spaced substantially horizontal rails, a carriage longitudinally slidably mounted upon the rails and provided near its forward end with a substantially vertical opening, the carriage being provided in its top with a substantially horizontal longitudinal recess forming a slideway which intersects the substantially vertical opening of the carriage, an ironing board disposed above the top of the carriage and including a depending leg slidably engaging within said substantially vertical opening, a longitudinally shiftable latch block slidably mounted within the slideway of the carriage, a spring connected with the latch block for shifting it longitudinally forwardly and into the substantially vertical opening below the depending leg for releasably holding the leg elevated, the latch block being retractible within the slideway and out of the substantially vertical opening so that the depending leg may move downwardly within the substantially vertical opening, and a substantially vertical guide device connected with the ironing board and with the carriage for limiting the upward movement of the ironing board.

4. The combination with a table including a top, of a pair of laterally spaced substantially horizontal rails mounted upon the table beneath

the top, a longitudinally shiftable carriage arranged below the top of the table and between the rails and slidably mounted upon the rails, the carriage including a pair of laterally spaced substantially horizontal elongated runners provided near their forward ends with aligned substantially vertical openings extending therethrough, the runners being provided in their tops with substantially horizontal longitudinal recesses forming slideways, the forward ends of the slideways leading into the substantially vertical openings of the runners, a vertically shiftable ironing board arranged adjacent to the forward ends of the runners and above the runners and including spaced depending legs slidably engaging within the substantially vertical openings of the runners, spring pressed latch members slidably mounted within the slideways of the runners and biased longitudinally forwardly and into the substantially vertical openings for engagement beneath the depending legs of the ironing board to releasably hold the ironing board in an elevated position, the latch members being retractible so that the ironing board may be lowered to an elevation below the table top, and guide means connecting the ironing board and runners for limiting the upward movement of the ironing board.
